UNITED STATES PATENT OFFICE.

EMMA STEPHENS, OF SILVER CLIFF, COLORADO.

STOVEPIPE-CLEANER.

1,161,355.

Specification of Letters Patent.

Patented Nov. 23, 1915.

Application filed June 8, 1915. Serial No. 32,896.

To all whom it may concern:

Be it known that I, EMMA STEPHENS, a citizen of the United States, residing at Silver Cliff, in the county of Custer and State of Colorado, have invented a new and useful Stovepipe-Cleaner; and I do hereby declare the following to be a full, clear, and exact description of the invention, such as will enable others skilled in the art to which it appertains to make and use the same.

This invention relates to an improved slide member for the elbow of a stove pipe designed to be raised and provided with means to receive the stove pipe cleaner, the object of which is to prevent the dust and the like from coming out into the room.

Another object is to provide a device of this nature comprising improved features of construction.

In practical fields the details of construction may necessitate alterations, falling within the scope of what is claimed.

The invention comprises further features and combination of parts, as hereinafter set forth, shown in the drawings and claimed.

In the drawings:—Figure 1 is a view in perspective of the elbow of a stove pipe, showing the slide and the cleaner as applied. Fig. 2 is a sectional view. Fig. 3 is a view showing the slide in detail. Fig. 4 is a sectional view on line 4—4 of Fig. 2. Fig. 5 is a detail perspective view of a modified form of the slide for the stove pipe cleaner.

Referring to the drawings, 1 designates the stove pipe, the outer wall 2 of the elbow portion 3 of which is provided with an opening 4, and upon opposite sides of the opening are flanges 5 which are inclined outwardly, downwardly and toward each other, and designed to overlie the slide 6, for guiding the slide during its vertical adjustment in said guide flanges. This slide 6 consists of two sections 7 and 8. The section 8 has an ear offset therefrom as shown, which ear 9 overlies and is pivoted at 10 to the section 7, so that the sections may have a pivotal action relative to each other. When the sections 7 and 8 are closed as illustrated in Fig. 1, the adjacent edges of the sections abut, and to hold the inner and outer faces of said sections flush with each other, when the sections are closed, the section 8 is provided with lugs 11 arranged in pairs, the lugs of each pair being opposite to each other, and so arranged as to lap over the section 7. The upper portion of the section 8 has a curved

projection or handle 12, to be grasped whereby the slide may be raised or lowered. The adjacent edges of the sections are provided with semi-circular cutaway portions 13, which register with each other when the sections are closed thereby forming the circular opening, which engages and receives the groove 14 of the sleeve 15. The groove 14 is of sufficient width to permit movement of the sleeve in the opening formed by the semi-circular cutaway portion 13, that is, incident to movement of the rod 16 (which passes through the sleeve) of the stove pipe cleaner 17, which is carried by the inner end 18 of the rod 16. The rod consists of two sections 19 and 20 (which section 19 has a handle 21) joined together or united at 22 by the threads as shown.

To apply the stove pipe cleaner to the stove pipe as shown, the sections 7 and 8 are first opened as shown in Fig. 3. The sleeve 15 is then arranged so that the cutaway portions 13 will engage the groove 14, and the section then closed, and partially inserted in the overhanging guide flanges 5. Prior to permitting the slide 6 being moved to the position shown in Fig. 1, the section 19 of the rod 16 with the cleaner 17 is inserted through the opening 4 of the elbow of the stove pipe, then the operator extends his or her hand through the opening 4, and brings the threaded end 21 back through the sleeve 15, after which the section 19 of said rod is connected to the section 18 as shown in Fig. 2, subsequently to which the slide 6 is moved to the position shown in Fig. 1. The stove pipe cleaner will then be moved back and forth through the sleeve, causing the blade 17 to scrape the carbon and the like from the inner surface of the stove pipe. In Fig. 5 a slide 6^a constructed in one piece is provided, instead of a sectional slide, and the upper portion of this slide 6^a is supplied with a curved projection or handle 6^b. However, the lower part of the slide 6^a is split as shown at 6^c with an opening 6^d at the crotch thereof, and through which opening the section 18 of the rod 16 reciprocates, when cleaning the stove pipe. When the slide 6^a is withdrawn from the flanges, the opposite edges of the split portion spring apart, so that upon reinserting the slide the split will arch down over the rod.

The invention having been set forth, what is claimed as new and useful is:—

In combination with a stove pipe elbow

having an opening in its outer convexed wall, guides upon opposite sides of the opening, a slide mounted in said guides, said slide consisting of two sections pivotally united, means for holding the adjacent edges of the sections alined with the opposite faces of the sections flush, the adjacent edges of the sections having semi-circular registering cutaway portions forming an opening, a sleeve having a groove engaging said open-

ing, and a stove pipe cleaner rod having a cleaner passing through said sleeve.

In testimony whereof I have signed my name to this specification in the presence of two subscribing witnesses.

EMMA STEPHENS.
